UNITED STATES PATENT OFFICE.

JAMES F. HOXSEY, OF WASHINGTON, DISTRICT OF COLUMBIA.

ADJUSTABLE LINER.

1,078,730.

Specification of Letters Patent. Patented Nov. 18, 1913.

Application filed November 21, 1912. Serial No. 732,671.

To all whom it may concern:

Be it known that I, JAMES F. HOXSEY, a citizen of the United States, residing at Washington, in the District of Columbia, 5 have invented new and useful Improvements in Adjustable Liners, of which the following is a specification.

The object of my invention is to improve upon that general type of device represented 10 in the patent to Howard, No. 796,213, August 1, 1905, for use in molds of the type employed in the familiar Mergenthaler linotype, where a base element adapted to be fixed at one side of the mold and an adjustable one engaging therewith are employed.

It is an important object to permit the size of the stationary or constant element to be reduced materially without limiting 20 the range of adjustment of the device, thus permitting the casting of a much longer slug with a constant element of a given range of adjustability with relation to the adjustable element, than in present devices.

25 A further important purpose is to so construct the two elements for coengagement that the adjustable member will always be free to swing outwardly on the constant member, thus avoiding liability of breakage 30 when the operator makes the common mistake of leaving too large an ejector blade in the machine after adjusting the device to cast a shorter line.

It is also an aim to construct the device 35 so that under normal operation, after adjustment and the first cast, the parts are held in rigid relation, so that the adjustment will not be disturbed under proper use of the casting machine.

40 It is a further attainment of the invention that the parts of the liner are formed to interlock with the filling of type metal for the establishment of their rigid relation, yet in such a way that when the device is 45 removed from the mold the filling will fall from place, without the necessity of any special tools and without liability of serious sticking, as has been found to occur in practice with previous devices.

50 Additional objects and advantages will be apparent from the following description or otherwise, and from the drawings, in which—

Figure 1 represents a familiar form of mold base and cap plate detached with my invention in operative position therebetween after use, Fig. 2 is a top view of the constant

member of my device, Fig. 3 is a bottom view thereof, Fig. 4 is a top view of the spacer member, Fig. 5 is a bottom view thereof, Fig. 6 is a rear edge view thereof, 60 Fig. 7 is a top view of the supplementary spacer for short slugs, Fig. 8 is a view of a slight modification of the device.

There is illustrated a mold including the base 11 and the cap plate 10 of any usual 65 construction, the base having the usual transverse channel or groove 12 at the left hand end ordinarily utilized to hold and align the usual one-piece liners used at this point. Engaged between the mold elements 70 there is a liner body or constant 13, corresponding in size to the ordinary solid liner, as to breadth and thickness, having the usual rib 14 on the under side engaging snugly in the groove 12, and having also the 75 slot 15 spaced longitudinally thereof from the rib, opening on the rear edge of the body and stopping short of the front edge a distance approximately one-third, more or less, of the width of the body.

80 The front edge portion of the body 13 is cut away as at 16 on the upper side for approximately half the thickness of the body, and for a suitable distance from the front edge, a series of longitudinally spaced 85 apertures 17 being formed therethrough at suitable intervals, preferably about 6 points printers' measurement. On account of the space ordinarily available in the mold wheel of the linotype, my device may be constructed 90 for use with that particular machine so as to project slightly beyond the left hand end of the mold. The body 13 projects inwardly of the rib 14 as at 18. The inner end edge is beveled toward the lower side, 95 and toward the rear this end is provided with a V-shaped bay or slot 19, the forward side 20 of which is inclined rearwardly from the angle outward, and the rear side 20' inclined away from the rib 14 toward 100 its outer end. The angular junction of the sides is located near the rib, and the sides are beveled toward the bottom side of the body. Recesses 21 in the form of small notches are formed on the under side of 105 the body opening from the edges of the slot 19, and having diverging sides.

110 The cut away portion of the front edge of the body 13 forms what may be termed a channel, extending throughout the length of the body, opening also through both ends, and a spacer 22 is provided having an arm

23 corresponding in cross sectional dimension and form to the slot and adapted to set snugly therein for adjustment longitudinally, having a pin 24 thereon adapted to engage snugly in one of the apertures 17. The inner edge and end of the arm 23 join on a curve concentric with the pin 24, so that the arm may be moved pivotally outward a distance when engaged in any of the 10 holes. A mold head 25 is carried on the inner end of the arm 23 with respect to the mold, having an outer mold face 26 at right angles to the arm 23, being of the full width and thickness of the slug to be cast, and 15 having the usual small teat 27 at the rear side projecting into the mold longitudinally. The back side 28 of this head, which is exposed at the back side of the mold slot, is inclined slightly toward the arm 23 from the 20 mold face 26 for an important function to be particularized. The head equals in breadth the arm 23, although this proportion is not arbitrary. The inner side of the head, disposed toward the constant member 25 of the liner, is beveled toward the lower side throughout its length including that portion over the base of the arm 23, which it will be remembered is but half the thickness of the head 25. Formed on the under 30 side of the head 25 there are notches 25' similar to those 21 on the constant element. It will be noted that these notches, while opening through the inner edges of the respective elements for the full height of the 35 respective edges, do not extend through the upper faces of the elements. They serve as additional irregularities to the slot 19 to prevent outward pivotal movement of the spacer or filling when a slug is ejected from 40 the mold.

In use, the constant member is engaged in the mold in the same manner that the usual one-piece left hand liner is, the slot 15 receiving the stop screw of the mold (not 45 shown). The channel or cut away part 16 is exposed at the forward edge, and before securing the cap plate of the mold, and while it is slightly raised, the pin 24 on the spacer is engaged in that opening which will allow 50 the mold face of the head 25 to lie spaced from the right hand end of the mold a proper distance to give the length of slug desired. For convenience the bottom face of the channel may be marked with a scale and 55 numbers indicating the length of line obtained by engagement of the spacer with the respective openings. The spacer is then swung inwardly until checked by engagement with the shoulder 29 comprising the 60 inner side of the channel 16. The cap plate is then secured in position in the usual manner, and the ordinary operation of the machine proceeded with. The casting of the first line fills the space between the head 25 65 and the constant 13, so that when the line

is ejected, if the proper ejector blade is employed, the temporary filling of type metal indicated at 40, will hold the spacer rigidly in position during ejection of the slug. It will be observed that a space is left beneath the arm 23 between the head 25 and the inner end of the constant 13, and in the operation of the usual linotype machine, the jaw of the matrice vise will close this opening and prevent the spilling of metal. Upon 70 removal of the complete device after use as described, the filling 40 will tend to drop out from between the members 13 and 22, without manipulation, but should there be any tendency to stick, which is not believed 75 likely, a slight upward lift on the head 25 while the constant is pressed downwardly will insure its dislodgment.

The inward inclination of the back face of the head 25 guards against accident in the 80 trimming of the slug, in case the mold is imperfectly formed and allows the spacer to swing inwardly too far, so that in the event that the head is forced too far in when adjusting the device, and it projects from the 85 back side of the mold slot, the back trimming knife of the linotype can not be damaged nor the spacer broken, as the spacer will simply be forced or fended outwardly because of the acute inclination of the back face 90 95 28 to the path of the knife, not affording such a hold for the knife as to result in cutting of the head 25 or nicking of the knife.

In Fig. 8, there is shown a different form 100 of the device which permits the portion 18 of the head to be made very short, and may be considered preferable to the first described form. Here, the inner end of the constant is simply formed with a keystone slot 41, opening thereon, all sides of which 105 are beveled toward the bottom of the device so that the temporary filling and buttressing type metal may fall out, as before described. This slot is located rearwardly of the series 110 of apertures 17.

It will be apparent that with the cap plate 115 of the mold lifted the filling 40 in either form of the device will exert no strengthening effect and will not hold the liner parts in rigid relation, for as soon as any pressure is applied to the rear side of the head 25, the liner parts will ride upward on the inclined surfaces of the filling, allowing their relative movement. It will be readily understood, however, that with the cap plate 120 clamped in position, the interlocking of the liner parts and the filling will be as secure as though the edge portions were vertical instead of beveled; indeed, the strength of the filling will be greater, on account of its 125 increased cross sectional measurement, due to the beveling of the edges of the liner parts, and especially so in the form shown in Fig. 8.

It may be stated that in practice, the fill- 130

ing 40 has never been found to stick, and always has fallen freely from between the parts of the liner, even without particular care in the oiling of the surfaces of the liner.

5 The angle of the back face of the head 25 with respect to the rear edge of the mold, in practice, is less than that shown in the drawings.

10 A scale 42 may be formed on the lower side of the channel 16 and numbers marked thereon to indicate in any suitable way the space between the head and right hand end of the mold, the present method being to indicate in point measure the space subtracted from the maximum length of the mold space by inward adjustment of the spacer.

What is claimed:

1. In a device of the class described, a 20 liner constant, means to fix the constant in a given relation to a mold, there being a channel formed in the constant longitudinally thereof spaced from said fixing means, and opening on the inner end of the constant, said channel extending longitudinally beyond the said fixing means, a spacer adapted to form one end of the mold space and having an arm thereon adjustable longitudinally in the channel, and means to 30 secure the spacer at any point of its adjustment.

2. In a device of the class described, a liner constant element having means thereon to fix it in a given relation to a mold, and having an edge adapted to be exposed through the front of the mold, a longitudinal channel formed in said edge opening on the inner end of the constant and open throughout its length on said edge, 40 a spacer having an arm longitudinally adjustable in said channel freely for lateral movement therefrom and means to secure the arm in adjusted positions against longitudinal and free for lateral movement, said 45 spacer having a head portion having a mold face adapted to form one end of the mold space.

3. In a device of the class described, a 50 liner comprising a constant element adapted to be engaged in fixed relation to a mold at one end, and having an edge portion adapted to be exposed through the front of the mold, a longitudinal channel being formed in said edge portion open throughout on said edge, and opening also on the inner end of the constant, a spacer element 55 adapted to form one end of the mold space, having an arm adjustable longitudinally in the channel, means to hold the arm releasably in adjusted position freely for lateral movement of the arm from the channel, said constant and spacer being shaped to interlock with a plastic filling therebetween under compression between mold base and top 60 to prevent pivotal movement of the spacer,

and for non-engaging relation therewith when relieved from coengagement of the mold parts.

4. In a device of the class described, a liner comprising a constant element adapted to be engaged in fixed position at one end of a mold, an adjustable head piece adapted to form the adjacent end of the mold space, the constant element having a longitudinal channel therein open on the inner end of the constant and throughout its length on the front of the liner, and a head piece adapted to form one end of the mold and having an arm pivoted for adjustment longitudinally of the channel and for lateral movement out of the channel at times, said constant and head being adapted to interlock with a plastic filling intervening against pivotal movement of the head with respect to the constant.

5. A device of the class described comprising a constant element adapted for fixed engagement in one end of a mold of the class described and having a channel therein adapted to extend longitudinally of the mold and to open on the front side thereof, a series of longitudinally spaced recesses being formed therein opening on the channel, a spacer element comprising a head piece adapted to close one end of the mold space and having an arm adjustable longitudinally in the channel means on the arm to engage the recesses against longitudinal movement of the arm in the channel, adapted to permit lateral disengagement of the arm, 100 opposed portions of the head and constant element having irregularities therein so disposed that when a plastic material is admitted therebetween and has become set, the liner elements will be held against relative lateral movement when clamped between the top and bottom elements of the mold, the sides of the liner elements abutting the plastic being beveled toward a common side, so that when free from the mold the filling 110 may fall therefrom.

6. In a device of the class described, an adjustable liner element having a mold face adapted to close one end of the mold space, and having a rear face inclined inwardly of the inner side of the said mold face, whereby when engaged by a back trimming knife in a casting machine of the class mentioned, the liner will be fended outwardly.

7. A device of the class described comprising a constant element adapted for fixed engagement in one end of a mold of the class described, and having a channel therein to extend longitudinally of the mold and to open on the front side thereof, a series of longitudinally spaced recesses being formed therein opening on the channel, a spacer element comprising a head piece adapted to close one end of the mold space and having an arm adjustable longitudi- 130

nally in the channel, means on the arm to engage the recesses against longitudinal movement of the arm in the channel and shaped and adapted to permit lateral dis- 5 engagement of the arm.

8. An adjustable liner comprising a constant element adapted for fixed engagement in one end of a mold of the class described, and having a channel therein to extend longitudinally of the mold, said constant projecting longitudinally outward beyond the ends of the top and bottom members of the mold, said channel extending throughout its

length, a spacer element having an arm longitudinally adjustable in the channel, and means coactive between the bottom of the channel and the arm to hold the arm in adjusted positions.

In testimony whereof I have hereunto set my hand in presence of two subscribing witnesses.

JAMES F. HOXSEY.
